UNITED STATES PATENT OFFICE.

WARREN R. WALKER, OF NEW DORP, NEW YORK, ASSIGNOR TO COOPER HEWITT ELECTRIC COMPANY, OF HOBOKEN, NEW JERSEY, A CORPORATION OF NEW JERSEY.

LIQUID-FLOW TIME SWITCH.

Application filed June 26, 1924. Serial No. 722,427.

My present invention relates to electric switches of the liquid flow type and particularly to such a switch in which there is a time lag in the circuit making motion.

5 For injecting a time lag in liquid flow type switches it has heretofore been general practice to employ either a baffle of insulating material with a small liquid passage formed therethrough or a restricted tube of 10 insulating material for the flow of the liquid from one position of the switch to another but these forms involve difficulties rising from a lack of a positive and definite make or break between the electrode terminals of 15 the switch in time relation to said liquid and said baffle.

I have discovered that by positioning one of the electrodes in such a switch close to or at the baffle thereof that the timing of the 20 making or breaking of the circuit is more accurately accomplished and more easily adjusted.

I have also discovered that by making the baffle of such a switch separate from the wall 25 of the switch container but suitably supported in close proximity thereto and having when necessary a restricted opening therein that the construction of the switch is considerably simplified.

30 In some switches embodying my invention I therefore make the timing baffle of conducting material and support it by means of a lead-in wire supported by the wall of the switch container. In other forms I make 35 the baffle of insulating material such as glass separate from the switch container but supported by one of the lead terminals of the switch which terminal has a portion exposed to connection with the switch liquid at said 40 baffle. In still other forms I make the baffle support and the lead separate but the electrode close to the baffle in which case the baffle may be either of insulating or conduct- 45 ing material.

45 For preventing the establishment of electrical connection in the switch immediately upon movements into the circuit making position, I provide the switch of my invention comprising a main inclosure or envelope with 50 an auxiliary chamber or cup which opens into the main envelope at a point below equilibrium level of the mercury therein in the closed circuit position but above intermediate levels. To allow the use of mini- 55 mum quantity of mercury in the switch I

provide an extension from the other electrode thereof into proximity to said first mentioned electrode but outside said auxiliary chamber. This allows of a simple construction in which the baffle and said extension are made of a unitary piece of metal and the use of the baffle support as the electrode lead.

It is an object of my invention to provide a liquid time switch of the baffle type in 60 which the relation between the making or breaking of the circuit between the electrodes therein is positive and definite with relation to the flow of the liquid of the 65 switch past said baffle.

It is also an object of my invention to provide a liquid flow time switch of the baffle type in which the baffle is separate from the 70 switch wall.

It is another object of my invention to 75 provide such a switch in which said baffle or a part thereof serves as one of the electrodes of the switch.

I employ the switch of my invention for automatically opening and closing the circuit of a load such as an advertising sign which is intermittently cut off and turned on at definite intervals for predetermined periods of time. Such a circuit and various 80 embodiments of my invention are shown in 85 the drawings in which:

Fig. 1, is an elevation view of an embodiment of the switch of my invention embodying a metal baffle with electrode extension thereon and a reentrant tube within which 90 terminates another electrode of the switch and which terminates just sufficiently below in equilibrium level in the circuit making position to insure proper conductance of current through the switch. In this view 95 the switch is shown in the circuit making position with the mercury flowing past the baffle.

Fig. 2, is a view similar to that of Fig. 1 with the mercury of the switch having at- 100 tained equilibrium therein.

Fig. 3 is a perspective view of the baffle of my invention with the baffle extension and the supporting lead therein.

Fig. 4 is a vertical sectional view of the switch of Fig. 1 along line 4-4 thereof showing an end view of the baffle of my invention.

In the drawing the tubular envelope 1 has mounted therein the metal baffle 2 by

means of the support lead 3 sealed through one end thereof. Said baffle is substantially a semi-circular disk positioned at right angles to the envelope tube in the lower part thereof with its curved contour in close proximity to the side of said tube. At the bottom of said baffle 2 is formed the inverted V notch 5 of a restricted area which allows passage of mercury therethrough. On said baffle 2 and extending longitudinally from the bottom thereof is formed the extension 44 which terminates within the body of mercury 9 of the switch in the closed circuit equilibrium position thereof. At the opposite end of said envelope 1 and at its bottom is formed the depression 7 through the bottom of which is sealed the electrode 6 which terminates below the surface of the mercury in the closed circuit equilibrium position thereof. Onto said depression 7 is formed the reentrant tube 8 which extends upwardly and terminates at a distance above the upper end of said electrode 6 and below the mercury in the closed circuit equilibrium position thereof. Said tube 8 forms with depression 7 an auxiliary chamber connecting with said main envelope through one opening which is at the top terminus of said tube 8. Support lead 3 is fixed to said baffle 2 in a manner to secure good electric conductance therebetween as by welding or brazing, and as shown in the drawings, for example, said extension 4 is made unitarily with said baffle 2 so that said extension baffle and lead form a continuous conductor from the mercury to the exterior of the switch when the switch is in the circuit making position for example as that shown in Fig. 2.

In the operation of the switch of my invention to establish a circuit therethrough with a time lag therein the switch is moved from a position in which the mercury 9 thereof is between the baffle 2 and the end of the envelope through which said electrode 3 is sealed into position as denoted by Fig. 1 in which the mercury will flow from the opening 5 at a retarded rate and will accumulate at the lower end of the switch where its level will rise during a definite period of time until it passes above the edge of said tube 8 whereby said main body 9 of mercury merges with the body 9' trapped in said auxiliary chamber 7, 8 and connection is established between said electrodes 3 and 6 through said baffle 2, extension 4 and mercury 9.

The tubular shaped member 8, it is to be understood, to meet certain kinds of service, will be made of a series of temperature resisting glasses, that is to say, the top rim may be a ring of quartz fused to the tubular member 8 if the thermal co-efficient expansion thereof permits of such juncture or a series of rings of suitable glasses may be interposed between the glass ring and the

glasses of the tubular member 8, all fused in juncture, or the top ring may be made of a suitable heat resisting glass having a greater co-efficient of expansion than that of glass and less than that of the container material, to withstand the ravages of high temperatures in service; or the tube 8 may be provided at its top with a cap piece of quartz, borosilicate glass, or other material capable of withstanding the effects of high temperatures at the point of the break between the mercury pool, and, by the use of either construction, the effects of high temperatures and rapid temperature fluctuations are not transmitted to the container material of the switch.

It is of course to be understood that when desired a proper atmosphere as of hydrogen, nitrogen, carbon dioxide, or any suitable gas or mixture of gases is provided in the switch envelope to aid in the dissipation of the heat of the arc, quenching etc.

I claim:

1. In a liquid flow time switch comprising a sealed envelope, a main chamber and a sub-chamber divided by a member terminating above the lower limits of said main chamber, mercury in said envelope sufficient to extend in said main-chamber and sub-chamber over said dividing member in a closed circuit position of the switch, electrodes sealed into said main chamber and said sub-chamber, and a flow restricting baffle across said main chamber in the path of mercury flow therein from an open circuit position to said closed position of the switch.

2. In a liquid flow time switch a sealed envelope comprising a main chamber and a sub-chamber divided by a member extending above the lower limits of said main chamber, mercury in said envelope sufficient to extend in said main-chamber and sub-chamber over said dividing member in a closed circuit position of the switch, electrodes sealed into said main chamber and said sub-chamber, and a flow restricting baffle across said main chamber in the path of mercury flow therein from an open circuit position to said closed position of the switch, one of said electrodes extending to and beyond said baffle in said main chamber.

3. In a liquid flow time switch comprising a sealed envelope, a main chamber and a sub-chamber divided by a tubular member terminating above the lower limits of said main chamber, mercury in said envelope sufficient to extend in said main-chamber and sub-chamber over said dividing member in a closed circuit position of the switch, electrodes sealed into said main chamber and said sub-chamber, and a flow restricting baffle across said main chamber in the path of mercury flow therein from an open circuit position to said closed position of the switch, one of said electrodes extending to

- and beyond said baffle in said main chamber.
4. In a liquid flow time switch comprising a sealed envelope, a main chamber and a sub-chamber divided by a member extending above the lower limits of said main chamber, mercury in said envelope sufficient to extend in said main-chamber and sub-chamber over said dividing member in a closed circuit position of the switch, an electrode sealed into said sub-chamber, a flow restricting baffle of conductive material across said main chamber in the path of mercury flow therein from an open circuit position to said closed position of the switch, a conducting support electrically connected to said baffle sealed through said envelope and a conductive member on said baffle in electrical connection therewith, and extending into said body of mercury in said closed circuit position of the switch, said conducting support serving both as a support for said baffle and lead for said conductive member.
5. In a liquid flow time switch comprising a sealed envelope, a main-chamber and a sub-chamber divided by a member terminating above the lower limits of said main-chamber, mercury in said envelope sufficient to extend in said main-chamber and sub-chamber over said dividing member in a closed circuit position of the switch, an electrode sealed into said sub-chamber, a flow restricting baffle across said main chamber in the path of mercury flow therein from an open circuit position to said closed position of the switch, a conducting support mounted on said baffle and sealed through said envelope, and a member of conductive material carried by said support and extending into the mercury in said closed circuit position of the switch.
6. In a liquid flow time switch comprising a sealed envelope, a main-chamber and a sub-chamber divided by a member terminating above the lower limits of said main-chamber, mercury in said envelope sufficient to extend in said main-chamber and sub-chamber over said dividing member in a closed circuit position of the switch, an electrode sealed into said sub-chamber, a flow restricting baffle of conductive material across said main-chamber in the path of mercury flow therein from an open circuit position to said closed position of the switch and in electrical contact with said mercury in said closed circuit position of the switch, and a lead support for said baffle of conductive material having electrical connection thereto and sealed through said envelope.
7. In a liquid flow time switch adapted to make a quick break of a circuit and a timed make, a sealed envelope having a main chamber, a sub-chamber connecting with said main chamber at a point above the bottom of the main chamber, an electrode sealed into said envelope and terminating in said sub-chamber, a contacting liquid in said container, a flow restricting baffle across the interior of said container in the line of flow of the liquid of the switch to and from said electrode, and a second electrode sealed into said envelope and terminating in the main body thereof.
8. In a liquid flow time switch adapted to make a quick break of a circuit and a timed make, a sealed envelope having a main chamber, a sub-chamber connecting with said main chamber at a point above the bottom of the main chamber, an electrode sealed into said envelope and terminating in said sub-chamber, a contacting liquid in said container, a baffle across the interior of said container in the line of flow of the liquid of the switch to and from said electrode, said baffle having a flow restricting passage for said mercury, and a second electrode sealed into said envelope and terminating in the main body thereof.
9. In a liquid flow time switch adapted to make a quick break of a circuit and a timed make, a sealed envelope having a main chamber, a sub-chamber connecting with said main chamber at a point above the bottom of the main chamber, an electrode sealed into said envelope and terminating in said sub-chamber, a contacting liquid in said container, a baffle across the interior of said container in the line of flow of the liquid of the switch to and from said electrode, said baffle having a flow restricting passage for said mercury and being positioned with respect to said wall to provide a space therebetween substantially greater than the volume of mercury therebetween in the closed circuit position of the switch, and a second electrode sealed into said envelope and terminating in the main body thereof.

Signed at Hoboken in the county of Hudson and State of New Jersey this 24th day of June, A. D. 1924.
